Primary Examiner — Barbara Fox*Assistant Examiner* — Mehri F Bajoul(74) Attorney, Agent, or Firm — Studebaker & Brackett PC(57) CLAIM

The ornamental design for a container for cosmetics, as shown and described.

DESCRIPTION

FIG. 1 is a perspective view of a container for cosmetics showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of FIG. 1 showing the state that a brush is combined to the container for cosmetics.

The broken lines shown in the drawings depict portions of the container for cosmetics that form no part of the claimed design.
